(57) **CLAIM**

The ornamental design for a steering wheel grip, as shown and described.

DESCRIPTION

FIG. 1 is a perspective view of a steering wheel grip according to our new design, in a first configuration; FIG. 2 is another perspective view thereof in a second configuration;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

In FIG. 1, the broken lines showing a steering wheel and a second steering wheel grip illustrate the environment of the claimed design and form no part thereof. The remaining broken lines show portions of the steering wheel grip which form no part of the claimed design.
